UNITED STATES PATENT OFFICE.

MOSES E. JOHNSON, OF PITTSBURG, PENNSYLVANIA.

WIRE BASKET.

No. 813,499.

Specification of Letters Patent.

Patented Feb. 27, 1906.

Application filed April 15, 1905. Serial No. 255,771.

To all whom it may concern:

Be it known that I, MOSES E. JOHNSON, a citizen of the United States, residing at Pittsburgh, in the county of Allegheny and State of Pennsylvania, have invented a certain new and useful Wire Basket, of which the following is a specification, reference being had therein to the accompanying drawings.

This invention relates to wire baskets, the object of the invention being to provide a light, strong, and durable basket composed wholly of wire and made in such manner that each and every basket will be of exactly the same weight, so that in weighing goods contained in the baskets it is unnecessary to weigh the baskets before and after filling, as the weight of the baskets is always a known quantity, never varying like the ordinary split baskets, due to changes in the weather.

20 The improved basket of this invention is particularly adapted for outdoor use in all kinds of weather, as it is not affected by excessive moisture. The basket is also better adapted for receiving and transporting heavy loads, as the construction provides for much greater strength than the ordinary basket in common use, while at the same time being productive of a lighter basket.

With the above and other objects in view, the nature of which will more fully appear as the description proceeds, the invention consists in the novel construction, combination and arrangement of parts, as herein fully described, illustrated, and claimed.

35 In the accompanying drawings, Figure 1 is a plan view of the blank from which the improved basket is made up. Fig. 2 is a perspective view of the complete basket, provided with rounded corners. Fig. 3 is a fragmentary view showing the basket provided with a square corner.

Like reference-numerals designate corresponding parts in all figures of the drawings.

The blank of which the basket is formed is shown in Fig. 1 and is composed of wire fabric, or, in other words, a fabric or body composed of wires of suitable gage crossing each other, preferably at right angles, and suitably united by welding the same electrically at all points where they intersect or cross. These fabric wires 1 extend continuously across the bottom of the basket and up the sides from top edge to top edge, where they connect to the selvage-wires 2, preferably of heavier gage and running along the upper edges of the sides, as shown, the fabric wires being by prefer-

ence wrapped or coiled terminally around the selvage-wires, as shown at 3, and being electrically welded at such points.

At the junction of the sides 4 of the basket with the bottom 5 are frame-wires 6, also preferably of heavier gage than the fabric wires, and these frame-wires are electrically welded to the fabric wires and cross each other at the bottom corners or angles of the basket, as shown at 7, and extend beyond said corners, at which points the frame-wires are upturned and extended to the upper edges of the sides, where they are electrically welded to the selvage-wires.

70 The blank is originally square or rectangular, and the corners are cut away by making V-shaped incisions, as shown at 8. The sides are then bent upward along the lines of the frame-wires until the projecting extremities of the horizontal fabric wires and the selvage-wires meet. Such meeting extremities are then brought together to form end-to-end butt-joints, which are then electrically welded at the points 9, thus making such 80 wires, in effect, continuous or endless and integral throughout and imparting great strength, rigidity, and durability to the basket as a whole.

85 The horizontal fabric wires of the sides and the selvage-wires where they project beyond the upturned end portions of the frame-wires may extend either in curved lines, as shown in Fig. 2, to establish rounded corners for the basket, or they may be extended in 90 straight lines, as shown in Fig. 3, to establish straight corners. In either event the sides of the basket are given an upward flare to enable a large number of baskets to be packed in a small space by nesting them one within 95 another.

By constructing the baskets in the manner described the strength of the same is greatly increased, they are much more durable, and they do not vary appreciably in weight, as is 100 always the case where the connecting or intersecting portions of wire baskets or receptacles are soldered or mechanically secured.

105 The baskets may of course be made in various sizes, depths, and capacities, the flare of the sides may be of any desired degree, and the wires may be of any suitable gage and placed at any desired distance apart in the manufacture of the baskets.

Having described the invention, I claim as 110 new—

An integral wire basket made up from a

blank substantially in the form of a Maltese cross and composed of crossed fabric wires, the wings of the cross forming the sides of the basket, frame-wires running along the junction of the sides and bottom and crossing each other at the lower corners of the basket, and selvage-wires running along the top edges of the sides, the selvage and fabric wires being

connected at the basket-corners by welded butt-joints

In testimony whereof I affix my signature in presence of two witnesses.

MOSES E. JOHNSON.
